UNITED STATES PATENT OFFICE.

RAYMOND B. PRICE, OF MISHAWAKA, INDIANA, ASSIGNOR TO RUBBER REGENERATING COMPANY, A CORPORATION OF INDIANA.

PROCESS OF TREATING TEXTILE MATERIALS.

1,197,396.

Specification of Letters Patent.

Patented Sept. 5, 1916.

No Drawing.

Application filed January 19, 1912. Serial No. 672,261.

To all whom it may concern:

Be it known that I, RAYMOND B. PRICE, a citizen of the United States, residing at Mishawaka, in the county of St. Joseph, 5 State of Indiana, have invented new and useful Improvements in Processes of Treating Textile Materials, of which the following is a specification.

My invention relates to the treatment of 10 textile material such as is used in the production of threads for after use in producing woven fabric, which threads may be also used alone or in the production of thickened threads or cables, and has for its object 15 to provide an improved method of either initially treating the material, or treating it at some stage in the manufacture of the article to be produced, or both.

In attempting to impregnate woven, 20 braided, knitted or felted fabrics by either the usual "frictioning" method or by application of paste or solution it has been found that where the threads or fibers come in contact with each other there is substantially 25 no penetration or permeation by the plastic material, and it is this difficulty that my present invention in part is intended to overcome.

In the manufacture of twisted threads it 30 is feasible to begin at the very first step, that is to say, to treat the material, such as cotton, before it receives its initial twist to form it into a strand, which, together with other strands, is to be used in forming a 35 thread. Thus, the cotton may have applied thereto a proper proportion of strengthening or binding material, such as rubber, preferably in the form of rubber cement or paste, and then be twisted to form a strand. 40 Or the material may be taken after the strands are formed, and each strand subjected to this operation and then twisted into thread.

In practice it may be found desirable to 45 operate on threads in the first instance, which may be done by untwisting them into their separate strands, then treating said strands separately, and finally retwisting said strands into the thread. In carrying 50 out this process, however, it will be found that the strands produced by untwisting the thread are inherently weak, and it will, therefore, be found highly desirable that the thread itself be given a preliminary treat-

ment prior to its being untwisted, which 55 treatment will be found to add materially to the strength of the strands produced by the untwisting of the thread. This step is, of course, followed by the separate treatment of the strands and then retwisting them into 60 the threads.

I also contemplate, if desired, that the threads so formed of the impregnated strands may be themselves treated, though 65 this step may not be necessary.

It will be found that threads formed of strands treated as above described will be as to their tensile resistance materially strengthened. Ordinarily, textile material is governed as to its strength by the length 70 of staple of its component fibers and their relative interlocking or twist, and the present process of treatment renders them comparatively independent of both of those factors.

It will frequently be found desirable that the strands before twisting or the thread produced by the twisted strands be also treated to relieve them of their sticky characteristics, due to the application of the 80 rubber. I contemplate employing for this purpose any substance capable of being absorbed by the rubber, or any substance capable of being dissolved or otherwise removed, such as powdered rosin, shellac, and 85 the like. When rosin is used the same will be absorbed during vulcanization, while with shellac the same would be preferably dissolved prior to vulcanization. A thin coat of balata will also be found to be eff- 90 cacious. By such treatment the threads may be in some cases more readily employed separately, particularly in connection with rubber, or they may be woven, knit or braided into a suitable fabric of any desired character, or a number of said threads may be 95 twisted to form an enlarged thread or cable.

I have found that the strands, or even fibers of cotton, for instance, when subjected to a so-called rubber solution or cement are 100 not permeated by the rubber, which deposits as a layer on the outside, the permeation being practically limited to the solvent or fluxing agent. Thus, solvents, such as naphtha, fill the air spaces of the fibers, and when the 105 cement dries the naphtha will have diffused out and been replaced by air. This action occurs even when fluid pressure is used to

drive the cement in the fibers, and it is my aim to overcome the same. This I may do by subjecting the material after it has been treated with the rubber solution or paste to the action of a fixed pressure, as by means of rolls. In carrying out this step, I prefer to dry the material after the application of the cement when that is used, and then subject it to the rolls. With paste this drying step is not usually necessary. Furthermore, the pressure rolls employed may, if desired, be operated in a vacuum, or a vacuum chamber may be disposed immediately in front of said rolls, through which the material will pass just before it reaches said rolls. Also, said rolls may be heated to assist the rubber in sealing the ducts of the fiber when flattened by the fixed pressure of said rolls. A somewhat similar result will be obtained by heating the material itself before subjecting it to the rolls. I may also dispense with the rolls, and first pass the material through a vacuum, then treat it with a rubber paste capable of filling or sealing the air ducts of the fibers, and in this operation heat may be employed at will. I also contemplate any combination or modification of these two processes.

It will be obvious that the advantage attained is the practical elimination of air, gas or volatile matter from the ducts of the fibers, thus obviating the expansion of any air, gas, etc., during the vulcanizing operation, which expansion would tend to prevent satisfactory adhesion between the rubber and the fibers.

It may be found advantageous to apply to the material being treated one or more supplemental coatings immediately after the squeezing operation by the rolls, said coating or coatings being of either the same substance previously used or some other substance, as desired, and such supplemental coating or coatings may also be employed where paste is used. I also contemplate combining the coating with the pressure feature, by employing as a coating material a paste, such as heated rubber, fluxed or not, as desired, and by passing through this the material to be treated while said paste is subjected to pressure of any desired degree. Obviously, this step may be preceded by subjecting the material to a vacuum as hereinbefore described. The paste, being more homogeneous than a rubber solution, gives less opportunity for final filling of the ducts of the fiber with air or other gas. I also contemplate previously treating the material with a penetrating substance, such as a salt, glycerin, melted sulfur, tar, and the like, which will displace from the air ducts in the fiber any volatile matter, expansive gas, and the like, which under the heat of vulcanization would tend to expand and interfere with the adhesion of the rubber.

This step is to be followed by coating the material with rubber in any desired form and in any desired way.

If desired, I contemplate singeing any of the materials hereinbefore referred to as intended to be treated, and at any stage of treatment.

Having thus described my invention, what I claim as new and desire to secure by Letters Patent is:

1. The process of treating textile material, which consists in treating a formed thread with a strengthening or binding medium, untwisting said thread into its separate strands, treating said strands with a strengthening or binding medium, and retwisting said strands into threads. 75

2. The process of treating textile material, which consists in treating a formed thread with a strengthening or binding medium, untwisting said thread into its separate strands, treating said strands with a strengthening or binding medium, retwisting said strands into threads, and treating said threads with a strengthening or binding medium. 80

3. The process of treating textile material, which consists in treating a formed thread with a strengthening or binding medium, untwisting the thread into its separate strands, exhausting, and treating said strands with a strengthening or binding medium, and retwisting said strands into threads. 90

4. The process of treating textile material, which consists in treating a formed thread with a strengthening or binding medium, untwisting the thread into its separate strands, exhausting, and treating said strands with a strengthening or binding medium, retwisting said strands into threads, and treating said threads with a strengthening or binding medium. 100

5. The process of treating textile material, which consists in treating a formed thread with a strengthening or binding medium, untwisting the thread into its separate strands, treating said strands with a strengthening or binding medium, subjecting said strands to the action of a fixed pressure, and retwisting said strands into threads. 110

6. The process of treating textile material, which consists in treating a formed thread with a strengthening or binding medium, untwisting the thread into its separate strands, treating said strands with a strengthening or binding medium, subjecting said strands to the action of a vacuum and a fixed pressure, and retwisting said strands into threads. 120

7. The process of treating textile material, which consists in treating a formed thread with a strengthening or binding medium, untwisting the thread into its separate 130

strands, treating said strands with a strengthening or binding medium, subjecting said strands to the action of a fixed pressure in the presence of heat, and retwisting said strands into threads.

8. The process of treating textile material, which consists in treating a formed thread with a strengthening or binding medium, untwisting the thread into its separate strands, treating said strands with a strengthening or binding medium, subjecting said strands to the action of a fixed pressure, retwisting said strands into threads, and treating said threads with an

15 air excluding medium.

9. The process of treating textile material, which consists in treating a formed thread with a strengthening or binding medium, untwisting the thread into its separate strands, treating said strands with a strengthening or binding medium, applying to the strands a coating of an anti-sticking

medium of such nature as not to materially affect the quality or nature of the strengthening or binding medium, and retwisting 25 said strands into threads.

10. The process of treating textile material, which consists in treating a formed thread with a strengthening or binding medium, untwisting the thread into its separate strands, treating said strands with a strengthening or binding medium, applying to the strands a coating of an anti-sticking medium capable of being subsequently absorbed or removed, and retwisting said 35 strands into threads.

In testimony whereof, I have hereunto set my hand in the presence of two subscribing witnesses.

RAYMOND B. PRICE.
